INTERNAL COMBUSTION ENGINE

Emil Schimanek, Budapest, Hungary

Application April 24, 1931, Serial No. 532,397
In Austria April 25, 1930

18 Claims. (Cl. 123—32)

This invention relates to internal combustion engines which work with fuel injection, more particularly Diesel engines. The known internal combustion engines with fuel injection work either with direct injection of fuel into the cylinder or else with injection of fuel into a preliminary chamber that precedes the working cylinder. In both cases the fuel passes into the working cylinder in an atomized but still liquid form. This method of injecting fuel has disadvantages, which render the employment of such engines, particularly in the case of small engines, impossible for high speeds of revolution. These disadvantages consist primarily in the fact that on the one hand the atomization and regulation of the quantities of fuel to be introduced, particularly in the case of small motors, are difficult to effect at a high speed of revolution, and on the other hand in the fact that delayed ignitions occur. At the high pressures and the high speeds of fuel injection that are necessary for the atomization of the fuel, the latter must be injected into the cylinder through small apertures or holes. Such small holes are very liable to become choked, and also become worn very quickly, which leads to disturbances of working. The delayed ignitions have their origin in the fact that the fuel, before it burns, must be converted from the form of a liquid to that of a vapour, the quantity of heat requisite for this purpose being taken from the highly compressed air in the cylinder.

Now the object of this invention is to obviate these disadvantages in a reliable manner, and the invention consists in the fact that the heating of the liquid fuel under pressure on its way to the working cylinder is effected under such circumstances that the temperature of preheating approaches as nearly as possible the vaporization temperature at the existing pressure, but cannot exceed the latter temperature, so that the maximum preheating of the fuel, which is practicable without risk of evaporation before injection is attained.

According to the invention this result is obtained by heating the fuel under pressure by means of a heating device with automatic regulation in dependence upon the vaporization temperature corresponding to this pressure, or the critical temperature, in such a way that the vaporization temperature is nearly reached but is not exceeded, thereby attaining the maximum preheating of the fuel that is possible without the risk of vaporization before injection.

By this invention it is made possible to intro-

duce the fuel into the cylinder at a higher pressure and at a higher temperature than corresponds to the critical pressure and the critical temperature, which is mostly already reached at pressures lower than that corresponding to the injection pressure, this being effected according to the invention by automatically regulating the heating effect in such a way that the formation of vapour cannot occur. The invention thereby also furnishes a means of successfully utilizing fuels that are difficult to vaporize for operating injection internal combustion engines, since the quantity of heat requisite for vaporization is already supplied to the fuel before injection.

Such heating has primarily the following advantages:—

(1) The volume of the liquid is increased by the heating, as a result of which both the fuel pumps and the holes in the injection nozzles are enlarged, and the operating, both as regards the accurate functioning of the pump and as regards the choking of the nozzle holes, is improved;

(2) Owing to the fact that part of the fuel, upon being injected into the cylinder, evaporates in consequence of the fall of pressure occurring on injection, the atomization is improved;

(3) Owing to the formation of vapour, and also owing to the better atomization, the combustion is promoted and the duration of combustion shortened.

By such a process the result is also obtained that motors working with fuel injection (Diesel engines) can be operated at a higher speed of revolution than they could without preheating.

The above-mentioned advantages may become still more marked the more highly the fuel to be injected is preheated under pressure. The limit of the preheating is given by the fact that the fuel injection pump should only draw in liquid, as otherwise, if fuel vapour is sucked in as well, the measuring becomes unreliable, because the volume of the vapour is much greater than that of the liquid.

The formation of vapour can be reliably prevented automatically according to this invention by effecting the heating of the liquid fuel not directly but with the aid of a heating liquid.

As a heating liquid there may be employed either the liquid fuel or other liquids, of which the vaporization temperatures corresponding to the various pressures are known. When the liquid fuel itself is employed as the heating medium, and the latter is at the same or a somewhat lower pressure than the fuel to be heated, the vaporization of the latter may be reliably pre-

vented by utilizing the vaporization of the liquid employed as the heating medium—in this case the same liquid as the fuel—for regulating the heater (electrical heater, lamp heater or the like), whereby a further rise of temperature is guarded against, or the vaporization temperature of the liquid heating medium, and at the same time therefore the somewhat lower temperature of the liquid fuel, is permanently secured, provided the heater yields sufficient heat, that is to say, provided the heater is designed for the maximum load.

The said advantages may however also be utilized to the utmost limit, without the employment of a heat-transmitting medium, by effecting the regulating of the preheating by means of the vapour pressure or the vapour density, or by the temperature of the fuel (liquid or vapour) to be injected, the various magnitudes being utilized either singly or in any desired combination.

The utilization of the fuel vapour, the vapour density or the temperature of the preheated fuel has the advantage that the desired regulating can be reliably obtained even in the case of those fuels for which, as mostly occurs in practice, the thermal properties (relationship between vapour pressure and temperature and so on) are unknown.

If the vapour pressure is to be employed for regulation, the heating will according to the invention be carried out in such a way that the liquid, during the heating, is warmer at the surface or in the neighbourhood of the surface than at the deeper parts of the liquid. The vapour that forms in the upper portion of the liquid is then utilized for regulating the heating, while from the lower and cooler portion of the liquid the pump sucks in the fuel to be injected.

Various forms of the process according to the invention are illustrated by way of example in the accompanying drawings, in which

Figure 1 shows for purposes of comparison the known means for injecting fuel into the working cylinder,

Figures 2 to 9 show diagrammatically in sectional elevation various examples of construction of the invention.

In the known fuel injection device illustrated in Figure 1, the liquid fuel is drawn in by suction by a fuel pump 1 through a suction valve 2, and is sprayed through a delivery valve 3, a pipe 4 and an atomizing aperture 5 into the cylinder 6, in which there moves a piston 7.

The injection aperture 5 is controlled by a valve 9, which may be constructed as the delivery valve of the pump. The injection valve may however alternatively be non-mechanically controlled. Substantially the same arrangement may be employed in the case of preparatory chamber injection.

In the example of construction shown in Fig. 2 the pipe 4, which leads from the pump 1 into the cylinder and in which the fuel is subjected to pressure, is so strongly preheated, electrically for example, by means of a heating coil 8, that upon the pressure being relaxed by the opening of the injection valve 9, the evaporation of the liquid fuel is brought about to an extent dependent upon the fall of pressure and upon the preheating.

Preferably the arrangement is such that the delivery valve 3 of the pump closes the pipe 4 at the inlet point, and the injection aperture is controlled by a separate valve 9. This prevents dis-

turbances occurring owing to any excessive preheating of the liquid fuel in the fuel pump.

The heating apparatus 8 is adjustably constructed to enable the temperature of preheating to be regulated in accordance with existing requirements. Thus for example if electrical heating from a source of energy 8a is employed, the intensity of the heating may be so connected with the engine governor 8b, operatively connected with a variable resistor 8c, that at higher governor positions, that is to say, at low loads, the heating is less effective than at lower governor positions, that is, at greater loads, since in the former case less liquid fuel has to be preheated than in the latter case. It is also advantageous to employ a pump 1, of which the pressure can be regulated manually or automatically. Between the fuel pump 1 and the cylinder 6 is arranged a pump, compressor or the like 12, 13, in which the liquid fuel preheated in the pipe 4 under pressure enters through the valve 10 as a mixture of liquid and vapour, while owing to the relaxation of pressure when the valve 10 opens, a portion of the fuel is vaporized. This mixture of liquid and vapour is subjected by the compressor piston 12 to a compression by which so much heat is supplied to the mixture of liquid and vapour that the liquid still contained in the mixture is wholly, or at least to some further extent, vaporized by the relaxation of pressure. Not only does this operation provide sufficient heat for the further vaporization of fuel not yet vaporized but also insures, upon admission of the fuel to the cylinder, a better atomization of the drops of liquid still present after the first atomization. The compressor piston 12 delivers the fuel through the aperture of the valve 5 that acts as a pressure-relieving aperture into the cylinder 6.

Figure 3 shows a constructional example in which the compression of the liquid already partially vaporized by the heating of the liquid and the relaxation of pressure, that is to say, of a mixture of liquid and vapour, is effected in the compressor 13 by the piston 12, not alone but mixed with air. This air may be taken either through the automatic suction valve 14 from the atmosphere or through the valve 15 from the cylinder in a pre-compressed condition. In this constructional form, as the compressor piston 12 descends, at first air flows through the pipe 16 into the cylinder, and then, when the piston uncovers the connection leading to the valve 10, there flows in a mixture of liquid and vaporized fuel, which is then compressed by the piston 12, and delivered through the valve 17, the pipe connection 11 and the injection aperture 5 into the cylinder 6. The valve 17 may even be omitted, its place as a delivery valve for the compressor being taken by the valve 9. Atomization upon relaxation of pressure in the cylinder is thus promoted by the expansion of the air compressed with the fuel. This form of the process also renders possible a lower liquid pressure on the delivery side of the fuel pump and a lower preheating of the liquid fuel as well as the adoption of smaller injection velocities and pressures for the injection of the fuel into the cylinder.

Figure 4 shows a constructional example with indirect heating of the fuel through the medium of a liquid serving as an intermediate heating means.

The electrical heating device 8 here acts not directly upon the liquid fuel, which, as in the examples previously described, is to be preheated while flowing under high pressure through the

5 pipe 4 to the injection aperture, but through the medium of a liquid which is provided in a chamber 17' surrounding the tube 4. This liquid may advantageously be the same liquid as the fuel employed. Should some other liquid be employed as a heating medium, the boiling points of this liquid corresponding to the various pressures must be known.

10 The chamber 17' is closed at the top by a piston 18 or by some other movable member, which is subject to the pressure of a spring 18a, and by means of a lever 19, which can rotate about a point 20, actuates a regulating device 21, by which the intensity of the heating means 8 is influenced. At the bottom of the chamber 17' is provided a shut-off member 22, by which any heating liquid that has escaped by leakage or otherwise can be replaced. The piston 1 of the fuel pump is so constructed that during the suction stroke it is moved by the cam 1d of a cam disc 1c and a lever 1b, but during the compression stroke is under the influence of a spring 1a, the liquid pressure produced being therefore unambiguously determined by this spring. This 25 spring is adjusted to the spring 18a of the piston 18 in such a way that the boiling temperature of the liquid, corresponding to the pressure prevailing, is the same as or higher than the boiling temperature of the heating liquid corresponding 30 to the pressure prevailing in the chamber 17'.

35 When the heat delivered by the heating means to the heating liquid is greater than that which is taken up by the liquid fuel flowing through the tube 4 to the cylinder upon being heated to a temperature in the neighbourhood of the boiling point, there is evolved in the chamber 17', at the liquid pressure determined by the pressure of the spring 18a, vapour which moves the piston 18 and diminishes the intensity of the heating until 40 the temperature of the heating medium in the chamber 17' is kept steadily at the level of the vaporization temperature. This temperature is therefore steadily maintained in the chamber 17' independently of whether more fuel or less fuel 45 is flowing through the tube 4 to the cylinder. This fuel is therefore always heated right up to that temperature which corresponds to the vaporization temperature of the heating liquid, which may be liquid fuel, at the pressure prevailing in the chamber 17'.

50 Figure 5 shows a constructional example in which a superheating of the fuel or a vaporization thereof is prevented by the fact that the heat transmitted to the liquid heating medium by excess heating generates vapour, which is condensed on a cooled surface 23a.

55 The heating device 8 is here represented as an electrical device, and by means of the heating liquid in the chamber 17' heat is transmitted to the liquid fuel flowing through the pipe 4. The pressure in the chamber 17' is adjusted by means of the piston 18 and the spring 18a, as explained in connection with the preceding example, and is harmonized with the spring 1a. 60 The heat transmitted to the liquid heating medium by overheating is here removed owing to the fact that the vapour produced by overheating passes through the pipe 17a into a cooling vessel 23, where the vapour is condensed. There will 65 therefore always prevail in the chamber 17' the boiling temperature which corresponds to the heating liquid at the pressure prevailing in the chamber 17', provided the heating means 8 is dimensioned to correspond to maximum loading. 70 Accordingly the fuel in the tube 4 is likewise

always heated to one and the same temperature, quite independently of the load.

75 Figure 6 shows a constructional example in which, when employing the fuel itself as a heating liquid, the pressure in the chamber 17' is connected with that in the tube 4 through the medium of the piston 18 in such a way that upon one side of the piston 18 there acts the pressure in the chamber 4, and on the other side of the piston there act the pressure in the chamber 17' and the pressure of the spring 18a, whereby the pressure in the chamber 17' is kept lower than that in the tube 4.

80 Figure 7 shows the solution, in which in the chamber 17' and in the chamber 4 the same pressure is established by connecting these two chambers with one another, in which case the pump delivers into a chamber 24, from which the pipes 4, 17b and 23a branch off. The vapour generated in the chamber 17' is here condensed in 85 the tube 17a and 23. In this case the pump 1 may be moved positively even during the delivery stroke instead of by a spring.

90 Figure 8 shows a constructional example of a step-by-step preheating of the fuel, which is regulated by the pressure of the vapour.

95 The pump 30 draws fuel by suction out of the tank 31 and delivers it into the first heating vessel 32. This vessel is heated by an electrical heating device 33 on the cylindrical surface. 100 The regulating of the heater is effected by means of a piston 34, which co-operates with the vessel 32, and which, by means of a lever 36 under the action of a spring 35, actuates electrical regulating means 37.

105 To the vessel 32 is connected at the bottom the suction pipe of a pump 38, which draws in fuel from the bottom of the vessel 32 and delivers it into the heating vessel 39, which is heated by an electrical heater 40, this heater being regulated by 110 a piston 41 through the medium of a lever 43 acted upon by a spring 42, and an electrical regulating device 44.

115 To the bottom of the vessel 39 is connected the suction pipe of a pump 45, which draws the fuel 120 out of the lower portion of the vessel 39 and delivers it directly or through a mechanically controlled valve 46 into the motor cylinder 47. In the former case, that is with direct delivery, the valve 46 is omitted, and the pump 45 delivers the fuel through an open nozzle 48 into the cylinder, in which case however the delivery valve of the pump is positively controlled.

125 The method of operation of the heat-regulating means is as follows:—

130 As soon as the temperature in the heating vessel 32, owing to the action of the heater, has exceeded the temperature corresponding to the vapour pressure, which is uniformly determined by spring pressure and by the diameter of the piston 34, there is produced on the surface of the heated liquid a little vapour, which moves the piston 34 upwards against the action of the spring, and thereby diminishes the heating until the temperature corresponding to the pressure established in the vessel by the force of the spring is maintained.

135 The form of the tank, which is a high vertical cylinder, and the arrangement of the heater in the cylindrical surface, have the result that the liquid in the neighbourhood of the surface will be a few degrees warmer than in the lower portion. The formation of vapour is therefore limited to the upper portion of the liquid, while from the lower portion, or in fact from the lowest point, 140

liquid is drawn out by the suction of the pump 38.

The pressure in the tank 32 and in the tank 39 can be regulated at will owing to the design of the springs 35 and 42 respectively.

5 The pump 45 sucks liquid from the vessel 39 under a lower pressure than that at which the injection is to occur.

It will be obvious that either direct injection or preparatory chamber injection may be employed.

10 The speed of revolution of the pump 45 is determined by the speed of revolution of the motor 47 and the number of strokes per cycle, while the pumps 38 and 30 may be operated at any convenient speed of revolution. The pump is thus 15 operated in timed relation with the engine, and in predetermined relation with valve 46 so that such pressure variations as occur in chamber 39, fall within a comparatively limited range. The resultant pressure rises in response to the super- 20 added pressure of generated vapor and causes actuation of the control device 44.

The heating of the fuel may alternatively be carried out in a single stage, by the aid of a single heating vessel. In this case the pump 30 and the 25 heating tank 32, together with the equipment thereof, are omitted and the pump 38 sucks directly out of the fuel tank 31.

If the regulating of the heater or of the fuel preheating is not effected by the vapour pressure 30 but by the vapour density, for the purpose of obtaining a preheating approximating to the critical temperature of the fuel, the regulating of the heater may be obtained with a suitable boiler water level protection apparatus, such for example as that shown in Fig. 9. The heating right 35 to the critical point has the advantage, in addition to those mentioned above, that at the critical temperature the liquid volume is a maximum, and at this temperature the liquid and the vapor have 40 the same volume, that is to say, the accurate measuring of the quantity of fuel sucked in by the pump cannot be disadvantageously affected by the pump sucking in a mixture of vapor and liquid. The regulating of the heating when the critical 45 point is to be reached may be carried out on the basis of the principle that at this temperature the vapor and the liquid are of the same volume and of the same density. Any automatic boiler water level regulating device can therefore be used as 50 described above, the action of these devices in general being based upon the fact that vapor and liquid are of different specific gravities, or influence the thermoconductivity or the electrical resistance differently.

55 In Figure 9 is shown as a constructional example a device which acts by electrical means. In the heating vessel 50, in which the liquid level is secured by means of a discharge pipe 51, an electrical conductor or an electrical resistance 52 is lodged in the liquid space and a second electrical resistance 53 in the vapour space of the vessel. Both resistances are made of a material of which the electrical resistance changes according to the nature or density of the medium in 55 which they are immersed, platinum wire being an example of such a material. The two resistances are connected in a Wheatstone bridge, which is formed by the resistances 52, 53, 54 and 55 and the bridge 56. So long as the densities of the 60 vapour and of the liquid are different, current flows in the bridge wire 56, which by means of a relay 57 closes a contact 58, whereby the current delivered by a source of current 59 flows through the heating wire 60 of the vessel 50.

As soon as the condition in the heating vessel

has reached the critical point of the fuel, the resistances 52 and 53 become equal in magnitude. The bridge 56 then carries no current, and the relay 57 allows the contact lever 61 to fall, whereby the contact 58, and therefore the heating circuit are interrupted.

What I claim is:—

1. A method of operating internal combustion engines with liquid fuel injection, particularly Diesel engines, comprising supplying liquid fuel 10 to the engine under pressure, heating the liquid fuel while on its way to the engine cylinder under pressure through an interposed liquid between the source of heat and the liquid fuel to be heated, the said liquid forming the means of transmitting heat from the source to the fuel, regulating the heating of the fuel to be injected to maintain the temperature thereof intermediate its vaporization temperature under pressure before injection and its vaporization temperature at the lower pressure within the cylinder to thereby maintain the fuel in the liquid state prior to its introduction into the cylinder and to provide sufficient heat in the fuel so that it is vaporized as a result of the heat contained there- 15 in when introduced into the cylinder at said lower pressure, and then injecting the fuel into the engine cylinder.

2. A method of operating internal combustion engines as claimed in claim 1, further comprising 20 interposing some of the fuel-liquid, as a means for transmitting heat, between the source of heat and the liquid fuel to be heated.

3. A method of operating internal combustion engines as claimed in claim 1, further comprising 25 utilizing the vapour of the heat-transmitting liquid as a means for automatically regulating the heating of the liquid fuel.

4. A method of operating internal combustion engines as claimed in claim 1, further comprising 30 utilizing the vapour of the heat-transmitting liquid as a means for automatically regulating the heating of the liquid fuel, the said vapour exerting a compensating action by its condensa- 35 tion.

5. A method of operating internal combustion engines with liquid fuel injection, particularly Diesel engines, comprising supplying liquid fuel to the engine under pressure, heating the liquid fuel while on its way to the engine cylinder under pressure, the heating of the liquid fuel being effected in such a manner that the fuel becomes warmer at and near the surface than lower down, and utilizing the vaporization of the liquid at the surface for regulating the heating of the 55 fuel to be injected to maintain the temperature of said fuel intermediate its vaporization temperature under pressure before injection and its vaporization temperature at the lower pressure within the cylinder to thereby maintain the fuel 60 in the liquid state prior to its introduction into the cylinder and to provide sufficient heat in the fuel so that vaporization results because of the heat contained therein when introduced into the cylinder at said lower pressure, and then introducing the fuel into the engine cylinder.

6. A method of operating internal combustion engines with liquid fuel injection, particularly Diesel engines, comprising supplying liquid fuel to the engine under pressure, heating the liquid fuel while on its way to the cylinder under pressure to a regulated temperature intermediate its vaporization temperature under pressure and its vaporization temperature at the lower pressure within the cylinder, the heating of the liquid fuel 70

being effected in a vessel of such height that the temperature in the lower part of the vessel is lower than that in the neighbourhood of the surface, the vaporization of the liquid at the surface being utilized for regulating the heating, and liquid fuel being withdrawn from the lower part of the said vessel by a fuel pump, for injection into the engine cylinder, at a temperature that is a few degrees below the saturated vapour temperature corresponding to the pressure prevailing in the heating vessel.

7. A method of operating internal combustion engines with liquid fuel injection, particularly Diesel engines, comprising supplying liquid fuel to the engine under pressure, heating the liquid fuel while on its way to the cylinder under pressure to a regulated temperature intermediate its vaporization temperature under pressure and its vaporization temperature at the lower pressure within the cylinder, the heating of the liquid fuel being effected in such a manner that the fuel becomes warmer at and near the surface than lower down, the vaporization of the liquid at the surface being utilized for regulating the heating, and the vapour pressure allowed being determined by means of an adjustable spring.

8. A method of operating internal combustion engines with liquid fuel injection, particularly Diesel engines, comprising supplying liquid fuel to the engine under pressure, heating the liquid fuel while on its way to the cylinder under pressure to a regulated temperature intermediate its vaporization temperature under pressure and its vaporization temperature at the lower pressure within the cylinder, the preheating of the liquid fuel being effected in successive stages, and in each stage to a temperature a few degrees below the saturated vapour temperature corresponding to the pressure prevailing in the said stage, and the pressure in the last stage being lower than the injection pressure.

9. A method of operating internal combustion engines with liquid fuel injection, particularly Diesel engines, comprising supplying liquid fuel to the engine under pressure, heating the liquid fuel while on its way to the cylinder under pressure, regulating the heating of the fuel up to the critical point by means of the density of the vapour to maintain the temperature thereof intermediate its vaporization temperature under pressure before injection and its vaporization temperature at the lower pressure within the cylinder to thereby maintain the fuel in the liquid state prior to its introduction into the cylinder and to provide sufficient heat in the fuel so that vaporization results because of the heat contained therein when introduced into the cylinder at said lower pressure, and then injecting the fuel into the engine cylinder.

10. A method of operating internal combustion engines with liquid fuel injection particularly Diesel engines, comprising supplying liquid fuel to the engine under pressure, heating the liquid fuel while on its way to the cylinder under pressure, regulating the heating of the fuel by means of the difference in physical properties between the vapour and the liquid to maintain the temperature thereof intermediate its vaporization temperature under pressure before injection and its vaporization temperature at the lower pressure within the cylinder to thereby maintain the fuel in the liquid state prior to its introduction into the cylinder and to provide sufficient heat in the fuel so that vaporization results because of the heat contained therein when introduced into the

cylinder at said lower pressure, and then injecting the fuel into the engine cylinder.

11. A method of operating internal combustion engines with liquid fuel injection, particularly Diesel engines, comprising supplying liquid fuel to the engine under pressure, heating the liquid fuel while on its way to the cylinder under pressure, regulating the heating of the fuel by utilizing the difference in density between the vapour and liquid fuel to maintain the temperature thereof intermediate its vaporization temperature under pressure before injection and its vaporization temperature at the lower pressure within the cylinder to thereby maintain the fuel in the liquid state prior to its introduction into the cylinder and to provide sufficient heat in the fuel so that vaporization results because of the heat contained therein when introduced into the cylinder at said lower pressure, and then injecting the fuel into the engine cylinder.

12. In an internal combustion engine of the character described having a source of liquid fuel, the combination of regulable means for heating the fuel prior to its injection into the engine to a point such that the fuel will be vaporized through the reduction of pressure and the heat contained in the liquid itself upon injection into the engine, means cooperating with said heating means for preventing the application of such quantities of heat to the fuel that it is vaporized prior to its injection, and means for injecting the heated non-vaporized fuel into the engine.

13. Means for preheating liquid fuel that is about to be injected into the engine cylinder of an internal combustion engine to a temperature almost but not quite as high as the vaporization temperature corresponding to the pressure of the liquid fuel, comprising a fuel chamber leading to the engine cylinder, a heating liquid chamber surrounding the fuel chamber and communicating directly therewith, and cooling means for condensing the vapour generated in the heating liquid chamber.

14. In an internal combustion engine of the character described having a source of liquid fuel, the combination of regulable means for heating the fuel prior to its injection into the engine to a point such that the fuel will be vaporized through the reduction of the pressure and the heat contained in the liquid itself upon injection into the engine, means cooperating with said heating means and actuated in accordance with the difference in physical properties between the vapor and liquid for preventing the application of such quantities of heat to the fuel that it is vaporized prior to its injection, and means for injecting the heated non-vaporized fuel into the engine.

15. In an internal combustion engine of the character described having a source of liquid fuel, a combination of regulable means for heating the fuel prior to its injection into the engine to a point such that the fuel will be vaporized through the reduction of the pressure and the heat contained in the liquid itself upon injection into the engine, means responsive respectively to the densities of the liquid fuel and its vapour, and means cooperating with said heating means and controlled by said density responsive means for preventing the application of such quantities of heat to the fuel that it is vaporized prior to its injection, and means for injecting the heated non-vaporized fuel into the engine.

16. In an internal combustion engine of the character described having a source of liquid

- fuel, the combination of regulable means for heating the fuel prior to its injection into the engine to a point such that the fuel will be vaporized through the reduction of pressure and the heat contained in the liquid itself upon injection into the engine, means cooperating with said heating means for preventing the application of such quantities of heat to the fuel that it is vaporized prior to its injection, said last mentioned means including means responsive to the vapour pressure of the fuel, and means for regulating said heating means to reduce the quantity of heat supplied to the fuel upon increase in vapour pressure thereof, and means for injecting the heated non-vaporized fuel into the engine.
17. In an internal combustion engine having a supply of liquid fuel, the combination of means for subjecting the fuel to pressure, means for preheating the liquid fuel to a temperature closely approaching but not exceeding its vaporization temperature corresponding to its pressure, means providing for a preliminary relaxation of pressure with vaporization of a portion of the

fuel, compressor means for compressing the mixture of vapor and liquid with the production of a quantity of heat, and means for injecting the fuel into the engine cylinder with further vaporization of the liquid portion thereof.

18. In an internal combustion engine having a supply of liquid fuel, the combination of means for subjecting the fuel to pressure, regulable means for preheating the liquid fuel to a temperature closely approaching but not exceeding 10 its vaporization temperature corresponding to its pressure, means providing for a preliminary relaxation of pressure with vaporization of a portion of the fuel, compressor means for compressing the mixture of vapour and liquid with 15 the production of a quantity of heat, additional regulable means for heating the fuel, means controlling said heating means and preventing operation thereof to effect premature vaporization of the fuel, and means for injecting the fuel into 20 the engine cylinder with further vaporization of the liquid portion thereof.

EMIL SCHIMANEK.
